D. K. WILSON & A. W. LEE.
MANURE SPREADER.
APPLICATION FILED AUG. 14, 1908.

921,045.

Patented May 11, 1909.

UNITED STATES PATENT OFFICE.

DALTON K. WILSON AND ARTHUR W. LEE, OF WATERLOO, IOWA, ASSIGNEES TO WILLIAM GALLOWAY COMPANY, OF WATERLOO, IOWA.

MANURE-SPREADER.

No. 921,045.

Specification of Letters Patent.

Patented May 11, 1909.

Application filed August 14, 1908. Serial No. 448,500.

To all whom it may concern:

Be it known that we, DALTON K. WILSON and ARTHUR W. LEE, citizens of the United States of America, and residents of Waterloo, 5 Blackhawk county, Iowa, have invented certain new and useful Improvements in Manure-Spreaders, of which the following is a specification.

Our invention relates to improvements in 10 manure spreaders, and the objects of our improvements are these: first, to provide an improved pawl - and - ratchet driving - mechanism for the movable conveyer-apron, adapted to be adjusted to vary the speed of 15 such apron, and second, to furnish adjustable means for connecting and disconnecting the rotatable distributing-drum from the source of power adapted to actuate it. These objects we have accomplished by the mechanism 20 which is hereinafter fully described and claimed, and which is illustrated in the accompanying drawings, in which:

Figure 1 is an elevation of the right-hand side of a wagon-box equipped with our improved pawl - and - ratchet driving - mechanism, and with our improved, adjustable connecting and disconnecting device; Fig. 2 is an elevation of the left-hand side of said wagon-box showing the similar connecting, 30 and disconnecting device for that side; Fig. 3 is a plan of the upper face of the medially-pivoted driving-lever for the ratchet-wheel, and Fig. 4 is an enlarged upper plan view of the details of the sliding-block and slideway 35 of said adjustable connecting and disconnecting device.

Similar numbers refer to similar parts throughout the several views.

The wagon-box 40 contains a movable 40 conveyer-apron 48, which has its side-chains driven by sprocket-wheels 63 on the transverse shaft 22 which is driven by the ratchet-wheel 21 on the right-hand side of the box. A distributing-drum 1 is mounted on a transverse rotatable shaft 2, the ends of the latter resting in bearings in rearwardly-extending brackets 8, the latter secured to the delivery-ends of the side-boards of the box 40 by bolts 61. Secured to the right-hand end of 45 the shaft 2 is a cam-wheel 6, and a driven sprocket-wheel 5 is secured to each end of the same shaft.

On each side of the wagon-box are secured 50 the parallel horizontal guide-bars 28, secured by bolts 23 and 27, and provided with longi-

tudinal slots 24 to receive the lugs or bolts 25, the latter passed through orifices in either end of a vertical plate 26, whereby the said plate, when adjusted along the wagon-box longitudinally, may be secured to said 60 guide-bars. The plate 26 is longitudinally slotted to form parallel bars, the latter acting as slideways for a slide 32, the latter being vertically grooved along the sides to hold it from becoming detached, but other securing 65 means may be used if desired. The slide 32 has a downwardly-extending arm 34, provided near its lower end with a plurality of orifices 35, in one of which a pintle 36 extending from the arm 37 may be mounted. 70 The arm 37 is secured to the end of a transverse rock-shaft 38 under the wagon-box mounted in hanger-bearings 39, said rock-shaft thus being secured to an arm 37 on each side. Each slide 32 is adapted to move up 75 or down within the ways in said plates 26. Each slide 32 has a transverse orificed seat for a transverse horizontally slidable shaft 33, each shaft being adjustably secured in its seat by a set-screw 31. On one end of each 80 shaft 33 are spaced collars 59 and 60, between which an idler sprocket-wheel 29 is rotatably mounted on the shaft. A sprocket-chain 30 on each side of the box connects the idler 29 and the driven sprocket-wheel 5 on 85 the distributing-drum shaft 2.

When the sprocket-chains 30 on each side are simultaneously lowered with the slides 32, they engage the teeth of sprocket-wheels 62 on each side, the latter being rotated by 90 means of any suitable source of power. When the chains 30 are elevated with said slides, they are disconnected from said driving-sprocket-wheels, and the rotation of the distributing-drum 1 is stopped. Another 95 arm 57 is secured to the left-hand end of the rock-shaft 38, and a connecting-rod 54 is pivoted to said arm 57 and to a hand-lever 43 which is pivoted at 55 to said box 40, and which works within a rack-bar 50 secured to 100 said box by bolts 49 and 51, the rack-bar having orifices 52 to receive detachable securing means from said lever. The moving back and forth of said hand-lever causes the elevation or lowering of the chains 30 simultaneously.

The adjustability of the slide-plate 26 longitudinally along the brackets 28 permits the taking up of any slackness in the chain 30. The adjustability of the connection between 119

the arms 34 and 37 permits the sprocket-idler 29 to be kept at an unvarying distance from the pitch-line of the driving-sprocket-wheel 62 when the chain 30 is lowered into engagement with the latter wheel, notwithstanding any change in height of bolster due to the changing of the box 40 from one set of running-gear to another.

The numeral 7 designates a medially-pivoted lever, whose rear end is recessed to receive an anti-friction roller 3 whose pintles 58 are rotatable in the bifurcations of the lever. The rear end of this lever is so located that its anti-friction roller 3 contacts 15 with the edge of the cam-wheel 6, whereby said cam-wheel causes a reciprocation of the lever when the shaft 2 is set in rotation by the mechanism hereinbefore described. A pulling-pawl 20 has its pintles 16 pivoted in bearings in the bifurcated forward end of the lever 7, said pawl engaging and being adapted to rotate the ratchet-wheel 21 when the said lever is reciprocated. A holding-pawl 4 is medially-pivoted on the same 25 fixed stud 13 as is the lever 7, and has its holding-end in engagement with the ratchet-wheel teeth, while its forward prolongation 14 is connected at 17 to a tension-spring 19 whose other end is connected at 18 to the 30 pulling-pawl 20. This resilient-connection between said pawls not only tends to keep the pawls in contact with the ratchet-wheel to click back thereover, but also aids in keeping the roller 3 in contact with the cam-wheel, and in balancing the lever 7.

A hand-lever 44 is pivoted to the box 40 at 47, and works in a rack-bar secured to said box by bolts 41 and 45. The rack-bar has holes 42 to receive detachable engaging 40 means on the lever to permit of its adjustment therewith. A connecting-rod 15 is swiveled to the lever 44 at 46, a lug 11 being located on the rear portion of said rod, also a slide 12, and a spring 10 between said lug 45 and slide, which thus furnishes a resilient contact-piece between said rod and an upright arm 9 on the lever 7, the rear end of the rod passing slidably through an orifice in said arm. When the hand-lever 44 is 50 shifted it causes this resilient-connection to press against the arm 9, and force the said connection to lie at a certain location within the path of travel of said arm, which varies the stroke of the lever and pawl 20, and thus 55 varies the speed of the apron 48 by the action on the ratchet-wheel 21. The resilient-connection prevents shock and breakage of parts when the shifting of the lever 44 is suddenly effected, by the yielding of the spring 11 60 which gives enough to allow for the inertia of the parts to be adjusted.

Having described our invention, what we claim as new, and desire to secure by Letters Patent, is:

65 1. In a manure spreader, in combination,

a wagon-box, a movable apron therein, a medially-pivoted lever, means for moving one end of said lever to-and-fro, a ratchet-wheel adapted to actuate said movable apron, a pulling-pawl pivotally connected to the other end of said medially-pivoted lever and adapted to operatively engage and actuate said ratchet-wheel, a medially-pivoted holding-pawl one member of which engages said ratchet-wheel, and a resilient-connection between the other member of the holding-pawl and the pulling-pawl adapted to keep both pawls in contact with said ratchet-wheel to click back thereover.

2. In a manure spreader, in combination, 80 a wagon-box, a movable apron therein, a medially-pivoted lever, means for moving one end of said lever to-and-fro, a ratchet-wheel adapted to actuate said movable apron, a pulling-pawl pivotally connected to the other end of said medially-pivoted lever and adapted to operatively engage and actuate 85 said ratchet-wheel, a medially-pivoted holding-pawl one member of which engages said ratchet-wheel, a resilient-connection between the other member of the holding-pawl and the pulling-pawl adapted to keep both pawls in contact with said ratchet-wheel to click back thereover, and adjusting-means 90 adapted to be interposed in the path of movement of said medially-pivoted lever to vary the amplitude of stroke of said lever and of its pulling-pawl.

3. In a manure spreader, in combination, 100 a wagon-box, a movable apron therein, a medially-pivoted lever, a rotatable shaft, a cam-wheel on said shaft, one end of said pivoted-lever being adapted to contact with and be actuated by said cam-wheel, a ratchet-wheel adapted to actuate said movable apron, a 105 pulling-pawl pivotally connected to the other end of said pivoted lever and adapted to actuate said ratchet-wheel, a medially-pivoted holding-pawl one member of which engages said ratchet-wheel, and a resilient 110 connection between the other member of the holding-pawl and said pulling-pawl adapted to keep both pawls in contact with the teeth of said ratchet-wheel to click back thereover.

4. In a manure spreader, in combination, 115 a wagon-box, a distributing-drum mounted on a rotatable shaft at one end of said box, a driven sprocket-wheel on each end of said shaft, a driving sprocket-wheel on each side of said box adapted to be actuated by means of any suitable source of power, parallel slotted guide-plates bracketed to each side of said box, a longitudinally-slotted slide-plate on each side of said box each plate having 120 sliding-connections with said parallel guide-plates and means for securing them together in a desired position of adjustment, a slide seated and slidable in the longitudinal slot in each of said slide-plates and each having a transverse slideway and a downwardly-ex- 125 130

tending arm with a plurality of longitudinally-alined holes in its lower part, a transverse rock-shaft supported under said box, a crank-arm extending from each end of said 5 rock-shaft and adjustably connected with the adjacent perforated slide-arm on the same side, means for rocking said rock-shaft in either direction, a shaft slidable in the slideway of each slide, means for securing 10 said shafts in an adjusted position in their slideways, an idler sprocket-wheel on each of said shafts, a sprocket-chain on each side of said box connecting said idlers and driven sprocket-wheels and adapted to be raised and 15 lowered by said slides to be disconnected from or placed in operative engagement with said driving sprocket-wheels simultaneously.

5. In a manure spreader, in combination, a wagon-box, a distributing-drum mounted 20 on a rotatable shaft at one end of said box, a driven sprocket-wheel on each end of said shaft, a driving sprocket-wheel on each side of said box adapted to be actuated by means of any suitable source of power, guide-plates 25 bracketed to each side of said box, a slide-plate on each side of said box each plate having sliding-connections with said guide-plates and means for securing them to said guide-plates in a desired position of adjustment, a 30 slide seated and slidable on each of said slide-plates, means for simultaneously raising or lowering said slides, an idler sprocket-wheel rotatably mounted on each of said slides, and a sprocket-chain on each side of said box 35 about the idler and driven sprocket-wheel and adapted to be raised and lowered out of or into driving contact with the driving sprocket-wheel on the same side by means of

the adjustment of said slides in their slide-ways.

6. In a manure spreader, in combination, 40 a wagon-box, a distributing-drum mounted on a rotatable shaft at one end of said box, a driven sprocket-wheel on each end of said shaft, a driving sprocket-wheel on each side 45 of said box adapted to be actuated by means of any suitable source of power, parallel slotted guide-plates bracketed to each side of said box, a longitudinally-slotted slide-plate on each side of said box each plate having 50 sliding-connections with said guide-plates and means for securing them together in a desired position of adjustment, a slide seated and slidable in the longitudinal slot of each of said slide-plates and each slide having 55 a downwardly - extending arm, an idler sprocket-wheel rotatably connected to each of said slides, a sprocket-chain on each side of said box about the driven and idler sprocket-wheels on the same side, a trans- 60 verse rock-shaft supported under said box, a crank-arm extending from each end of said rock-shaft and connected pivotally to the end of the adjacent slide-arm, and means for 65 rocking said rock-shaft to a desired amount of adjustment forward or back to cause the said slides to connect or disconnect the said sprocket-chains simultaneously with or from said driving sprocket-wheels.

Signed at Waterloo, Iowa, this 27th day of 70
July, 1908.
